(57) **CLAIM**

(21) Appl. No.: **29/273,800**

The ornamental design for a head light for a motorcycle, as shown and described.

(22) Filed: **Mar. 13, 2007**

DESCRIPTION

(30) **Foreign Application Priority Data**

Sep. 20, 2006 (JP) 2006-025070

FIG. 1 is a front elevational view of a head light for a motorcycle showing my new design;

(51) **LOC (8) Cl.** 26-06

FIG. 2 is a left side elevational view thereof;

(52) **U.S. Cl.** **D26/28**

FIG. 3 is a right side elevational view thereof; and,

(58) **Field of Classification Search** D26/28-36;

362/459-468, 475-478, 485-487

See application file for complete search history.

FIG. 4 is a top plan view thereof.
The broken line showing of the environment is for illustrative purposes only and forms no part of the claimed designs.
The portion encompassed by a solid line is the design sought to be patented.
